MULTICYLINDER COMBUSTION MOTOR

Application filed January 7, 1927, Serial No. 159,708, and in the Netherlands January 15, 1926.

This invention relates to the distribution of liquid fuel over the cylinders of internal combustion motors.

The correct distribution of the required fuel in combustion motors is of great importance if the normal development of power is required because if the distribution is disproportionate one or more of the cylinders are undercharged and the other cylinders on the contrary are overcharged.

The object of the invention is to render a uniform distribution of the liquid fuel over all the cylinders possible notwithstanding the unequal leakages along the pistons of the needle-valves in an upward direction, so that notwithstanding the differences in the leakages an equal charge in all of the cylinders is continuously secured.

In order to make certain that each spraying-nozzle has the same quantity of fuel supply it is desirable to use one single fuel-pump for all cylinders and to let the pump make as many strokes as injections are required. The pump then can act on one main conduit with branch-pipes to the different spraying-nozzles, so that each delivery-stroke of the pump causes the pressure to vary up to a few hundred atmospheres pressure on the fuel behind the pistons of the needle-valves.

In this way all the nozzles are connected at the same time to the fuel-supply under the same pressure, independent of the cylinder which is to be provided with fuel, so that always the same quantity of fuel leaks away. If the piston does not fit tightly in its cylinder, the leakage will result in an escaping of the fuel along the piston in an upward direction, but since all the nozzles are connected to the fuel supply under the same pressure, the delivery strokes of the pump will effect the same pressure on the fuel below the piston of the needle-valve and hence the same quantity of fuel will be supplied to each of the cylinders. In this way no difference arises in the quantity of injected fuel.

According as to whether the motor is more or less charged the quantity of the fuel to be injected is regulated by making the pump-stroke longer or shorter or with the aid of an adjustable overflow-valve. The spring-

pressure of the needle-valves being lowered successively at the moment of injection of the fuel so that the pressure of the fuel is able to open the valve for the cylinder in question. The spraying thus only takes place in that cylinder for which the spring-pressure on the needle-valve is lowered temporarily.

So with such a device each cylinder always has, independent of the differences in leakages of the needle-valves, the same quantity of fuel supplied since all the leakages are replenished by the mutual main conduit.

The temporary decrease of the spring-pressure of the needle-valves can be obtained in different manners, for instance by using a counter-spring.

According to the present invention the desired result is attained by means of a shaft carrying a plurality of cams which actuate a lever associated with the needle valves. The rotating of each cam effects a partial neutralizing of the spring pressure of the needle valve at a predetermined time. One form of my invention is shown in the accompanying drawing.

On the cam-shaft 1 a number of cams 2 are mounted corresponding with the number of needle-valves against which the rollers 3 of the levers 4 rest. On the spring 6 of the valve-box 7 an adjusting-screw 5 connected to the lever 4 rests. In the position shown, no extra pressure on the spring is effected by the screw 5, so that in that moment the needle-valve can open under the influence of the pressure of the supplied fuel and thus the fuel can be injected into the cylinders 11.

The spring-stress then namely is lower than the influence of the pressure of the fuel in the main-conduit 8 on the piston 9 which leads from the power pump 12, so that the latter is moved against the action of the spring and the needle-valve 10 is opened so that the required injection will take place. During this time the springs of the other needle-valves are stressed stronger as the corresponding rollers 3 of the levers 4 are pressed up by the larger diameter of the cylindrical part of the cams 2, causing the screws 5 to exercise more stress upon the springs 6. The

tension stress of the springs will close the respective needle valves tightly on their seats.

So it is clear that with the alternative decrease of the spring stress of the needle-valves it is attained that the supplied fuel can be injected past only one of the needle-valves at a time.

It will be obvious that when the parts are in the position as shown that the cam controlling the left-hand cylinder is turned towards its coating roller with its flattened part. Hence no extra pressure is exerted by the lever on the spring of the left-hand piston and said piston will be pressed upwardly by the fuel, and in consequence the needle valve will open and fuel is injected into the left-hand cylinder. At the same time the cam 5 for the right-hand piston is turned from the roller thereof with its rounded part. Consequently the pressure of the right-hand spring 6 is increased by the associated lever and the pressure upon the fuel will not be sufficient to move the right-hand piston in an upward direction to open the needle valve. Hence no fuel will be injected into the right-hand cylinder.

I claim:

A fuel-injecting device for multi-cylinder combustion engines having a needle valve for each cylinder adapted to inject fuel into said cylinder, a spring associated with each needle valve, a source of fuel supply connected to each valve and having a pressure substantially equal to the normal spring pressure of the needle valve, a cam shaft and rocker arm mechanism associated with said springs and adapted to increase and decrease the pressure of said springs at predetermined time intervals whereby the needle valves are held in closed position by said spring pressure, and released at a predetermined time by the pressure of the fuel to inject fuel into the cylinders.

Amsterdam, this 27th day of December, 1926.

In testimony whereof I have signed my name to this specification.

JAN BRONS.
